WARD R. KELLEY, OF LOS ANGELES, CALIFORNIA

ROTARY DRAW WORKS BRAKE

Application filed September 22, 1930. Serial No. 483,653.

The prime object of my invention is to provide a brake suitable for the heavy duty and extreme wear encountered in the draw works of a rotary or other drilling rig.

5 An object of my invention is to so subdivide and mount the lining within a brake band that any desired portion of the length of the lining may be removed and replaced without replacing the remainder.

10 An object of my invention is to provide means for removing worn-out sections of the lining and for moving less worn sections into the positions formerly occupied by the removed portions.

15 An object of my invention is to provide a brake lining which may easily and cheaply be affixed to interchangeable shoes and transported to the location at which said shoes are to be used.

20 In drilling oil wells the wire line on which casing and drill pipe are raised and lowered is wound on a reel to which is affixed a brake drum controlled by brake bands. For lowering and controlling a long string of casing or pipe a very heavy drum is required and the band linings are proportionately large and are subject to excessive wear.

25 Not only are these massive linings very costly in themselves, the highest possible grade of material being used, but also the labor and loss of drilling time involved in dismounting the band, removing and replacing the worn lining and remounting the band are all sources of undue expense.

30 Oil well band brakes are uniformly constructed with one end fixed to a stationary pin and the opposite end moved by a lever—thus in Fig. 1 the loop A is pivoted on a fixed pin while the loop B is moved by a hand lever, not shown, in the direction indicated by the arrow B, to tighten the band and apply the brake. Ordinarily the drum revolves within the band, while lowering, in the direction indicated by the arrow C, or from the 35 fixed end toward the free end of the band.

40 It will be evident that when the drum revolves in this direction while braking, that portion of the band adjacent the free end will bear on the drum with much less force than will that portion of the band adjacent the

fixed end. The former is pressed against the drum only by the force exerted through the hand lever while the latter is pressed against the drum by an additional force due to the drag of the band on the drum. In consequence the entering end of the band wears away its lining much faster than the parting end, and the former is usually entirely worn through before more than a third of the total mass of lining is worn away.

45 In my improved design the brake lining is divided laterally into sections each of which is mounted on a block or shoe arranged to be moved longitudinally on the band proper and to be retained at the parting end (toward which the shoes are urged by the friction of the drum) by abutment against the end loop or some other object attached to the end of the band.

50 In one modification of the invention each individual shoe may be removed from the inner side of the band; in another modification removal is effected from an end of the band, but in either modification it is possible to remove any worn out sections, move less worn sections into the positions formerly occupied by those completely worn, and place new sections in the positions formerly occupied by those least worn. This removal and transposition may be effected without removing the band from its mounting, it being only necessary to slacken the band when the first modification is used or to disconnect one loop when using the other.

55 By the use of my improved band great advantages may be realized:

A. It is possible to use compressed block lining which is much more durable and less expensive than band lining but cannot be transported, in the sizes required for draw-works brakes, without breakage.

B. As shoes are removed only when the lining on such shoe is completely worn out there is no wastage of unworn lining.

60 C. As the shoes are gradually moved around the band from points of less wear to points of greater wear and new blocks inserted in the positions formerly occupied by those least worn, the circle of lining is con-

stantly maintained in substantial conformity to the curvature of the drum.

D. As only a small portion of the lining is renewed at any one time the tedious and often dangerous breaking in of new linings is avoided.

E. The labor incident to attaching the lining to a number of shoes sufficient to line the band is much less than that incident to attaching a strip lining to the band itself, and this labor can be performed in a properly equipped shop and the lined shoes taken to the rig instead of making the renewal in the field.

F. Distortion of the band by repeated removal and replacement and by repeated attachment of new linings is entirely avoided.

G. The band proper may be a continuous piece of steel of exactly the desired flexibility and resiliency and need not be weakened by bolt or rivet holes.

H. By making the shoes relatively short the band proper is permitted a much greater flexibility than when relatively long lining sections are attached directly to the band.

Other objects and advantages of my invention will be evident on inspection of the attached drawings and the following description thereof, in which:

30 Fig. 1 is a side elevation of a complete band with shoes and lining sections in place;

Fig. 2 is a plan view of a part of the band seen from the outside, showing the method of attaching the shoes in one modification of 35 my invention;

Fig. 3 is a cross section on the line 3—3 of Fig. 2;

Fig. 4 is a plan view of a modified form of shoe;

40 Fig. 5 is a side elevation of the modification shown in Fig. 4, and

Fig. 6 is a cross section of the same modification on the line 6—6 of Fig. 5.

Referring to the drawings, 10 is a continuous band of flat steel formed to the curvature of the brake drum but of somewhat greater diameter. To the ends of this band are attached the loop 11 which passes around a fixed pin 12 and the loop 13 which passes 45 around a lever actuated pin 14, this pin moving the free end of the band, in the usual manner, in the direction indicated by arrow B, to tighten the band and its attached members against the drum.

50 55 If the type of lining shoe shown in Figs. 2 and 3 is used at least one and preferably both of the loops must be readily detachable as by means of the bolts 15—15, but if the modification shown in Figs. 4, 5 and 6 is used 60 the attachment of the loops may be permanent if so desired.

Within this band and between the band and the drum I place a plurality of shoes 16 to each of which is attached a block or strip 65 of lining material 17. The various manners

of attaching brake lining to bands or shoes is well known and understood. In Fig. 5 I indicate flat head screws 18—18 without limiting myself to this or any other specific method of attachment which, however, should be of such nature that the remains of a worn lining may be removed and a new lining inserted in the shoe without excessive labor.

70 Between the ends of the shoes I prefer to place filling strips or spacers 19 fitting loosely around the band and adapted to prevent the ends of the shoes from chafing. The use of these filling strips is desirable but not essential. The ends of the band must be provided with some sort of projection to serve as an abutment for the end shoes. In Fig. 1 these abutments are shown as the ends 20—20 of the straps from which loops 11 and 13 are formed. Such number of shoes should be placed on the band as will almost but not quite occupy its length; the shoes must not be so closely placed as to interfere with the free flexing of the band.

80 85 In the modification shown in Figs. 1 to 3 the shoe is retained on the band by means of lugs 21 extending over its edges. In this modification the shoe can be placed and removed only from an end of the band, requiring the removal of at least one of the loops 11 or 13.

90 95 In the modification shown in Figs. 4 and 6 the shoes may be placed from below or within the band, the side lugs 22 retaining the shoe against side movement and the through bolts 23 holding it in place on the band.

100 105 In either modification a slight clearance in both directions should be allowed in order that the shoe may be moved longitudinally on the band without binding, so that when a worn section is removed from one end the remainder of the shoes may be moved around the band for a corresponding distance and a newly lined shoe placed at the opposite end to fill the space thus formed. The upper face of the shoe in either form may be provided with ribs as at 24 in order that nuts 25 may be placed on the lining attachment screws 18.

110 115 The objects and advantages of my invention will not be fully realized in any device in which a worn section is removed and a freshly lined section put into the space created by such removal, inasmuch as the new section thus positioned would project materially beyond the curve formed by the uneven wearing of the lining, holding adjacent portions of the band out of contact with the drum until the new section had been worn down to conform to the curvature of 120 the remainder of the lining.

125 I claim as my invention:

1. A brake band for an externally contracting brake comprising a flexible metallic band having a loop member removably 130

bolted to each end of the band in such a manner as to constitute an endwise stop for the brake lining, a plurality of shoes comprising metallic backing pieces having two or more pairs of lugs extending behind the band, brake lining sections attached to the inner faces of said shoes, transverse openings through each of said lugs and a bolt attached through the openings in each opposite pair of lugs, said bolt extending across the back of said band.

2. A brake band for an externally contracting brake comprising a flexible metallic band having a loop member attached to each end of the band in such a manner as to constitute an endwise stop for the brake lining, a plurality of shoes comprising metallic backing pieces having two or more pairs of lugs extending behind the band, brake lining sections attached to the inner faces of said shoes, transverse openings through each of said lugs and a bolt attached through the openings in each opposite pair of lugs, said bolt extending across the back of said band.

25 In witness that I claim the foregoing I have hereunto subscribed my name this 16th day of September, 1930.

WARD R. KELLEY.
